COMBINED LIGHT AND SIGNAL FOR
AUTOMOTIVE VEHICLES

John J. Manning, Grosse Pointe, Mich.

Application June 2, 1952, Serial No. 19,992

Term of patent 14 years

(Cl. D48—32)

To all whom it may concern:

Be it known that I, John J. Manning, a citizen of the United States of America, residing at Grosse Pointe, county of Wayne, State of Michigan, have invented a new, original, and ornamental Design for a Combined Light and Signal for Automotive Vehicles, of which the following is a specification, reference being had to the accompanying drawing, forming part thereof.

Fig. 1 is a side elevational view of a combined light and signal for automotive vehicles, showing my new design.

Fig. 2 is a perspective view thereof to a smaller scale, the dotted line showing of a portion of an automobile being for illustrative purposes only.

Fig. 3 is a front elevational view.

Fig. 4 is a rear elevational view.

Fig. 5 is a cross sectional view taken on the line 5—5 of Fig. 1.

The dominant features of my design are shown in solid lines.

I claim:

The ornamental design for a combined light and signal for automotive vehicles, substantially as shown and described.

JOHN J. MANNING.
